SAFETY ATTACHMENT FOR SKIS

René Rossellat, Tartegnin, Vaud, Switzerland, assignor to Gisèle Rossellat-Ray, Tartegnin, Vaud, Switzerland

Filed Mar. 28, 1963, Ser. No. 268,639

4 Claims. (Cl. 280—11.35)

The present invention relates to a safety attachment for skis. This attachment is characterized by the fact that it comprises, in combination, on the one hand a heel-piece fixed to the ski as to be able to move slowly in a direction perpendicular to the latter and on the other hand a stop element for the toe of the boot, rotatably mounted on a pivot-pin perpendicular to the plane of the ski and subjected to the action of a resilient device which tends to maintain it in the axis of the latter, the said pivot-pin being mounted on a support sliding longitudinally on the ski and subjected to a flexible knuckle-joint tension device, provided with a control lever which permits of pressing the said stop element against the boot bearing on the said heel-piece.

The accompanying drawing shows, by way of example, one embodiment of the object of the invention.

FIG. 1 is a view in elevation of a safety attachment for skis, provided with a boot.

FIG. 2 is a plan view, the boot being removed.

FIG. 3 is a cross-section of a detail to an enlarged scale, along line III—III of FIG. 2.

FIG. 4 is a cross-section of a detail to an enlarged scale, along line IV—IV of FIG. 2.

FIG. 5 is a profile view, partly in cross-section, of the heel-piece.

The attachment shown comprises a heel-piece including a base 1 secured to the ski 2. This base is provided with two columns 1a (FIG. 5) perpendicular to the plane of the ski on which slides the body of the heel-piece. Each column 1a surrounds a coil-spring 4 bearing on an inner end shoulder 1b of the column and on a nut 5 carried by a threaded rod 6 provided with a control head 6a. This control head bears on the upper surface of the body 3 of the heel-piece. By screwing more or less the heads 6a one varies the tension of the springs 4, each nut 5 being prevented from rotating by engagement with the inner wall of the respective column 1a, which has a non-circular shape. The springs 4 thus tend to maintain the body 3 against the base. The heel-piece finally includes a rib 7, in the shape of an arc of a circle (FIG. 4) of semi-circular straight cross-section, designed to engage in the groove 8 in the heel of a boot 9.

This rib 7 is provided, on its rear face, with flutes 10 engaging flutes 11 on the body 3 which permits of adjusting the height of the rib relative to the latter; a screw 12 serves to lock these two elements together. Thus, the height of the rib 7 may be adapted to the height of the groove in the boot.

The attachment shown further comprises a stop element 13 for the front end of the boot. This stop element is provided with a fluted portion 14 (FIG. 3) bearing against the toe of the boot. It is mounted rotatably on a pivot-pin 15 itself screwed on a threaded rod 16. This latter, extending perpendicularly to the plane of the ski, is carried by a plate 17 sliding longitudinally on the ski, between the side rims 18a of a slide 18 screwed on the ski. By screwing more or less the pivot-pin 15 on the threaded rod 16, one varies the height of the stop element 13 relative to the ski.

The pivot-pin 15 is integral with a flexible strip 15a the end of which is secured to the plate 17 by a screw 19, thus preventing the pivot-pin 15 from rotating inopportune.

A radial hole 20 is bored through the stop element

2

13, a ball 21 and a spring 22 acting thereon being housed in the said hole. A screw 23 permits of adjusting the tension of this spring. The pivot-pin 15 has a hole 24 bored therethrough in which the ball 21 partly penetrates thus ensuring the stability of the stop element 13 when it is located in the axis of the ski. If the boot exerts a lateral thrust thereon exceeding a definite amount, for example in the case of a fall of the skier, the stop element 13 rotates about the pivot-pin 15, the ball 21 moving in opposition to the spring 22, thus freeing the boot and avoiding the risk of an accident through twisting of the foot. A tension device is provided to move the stop element 13 in the direction of the heel-piece 3 and thus tighten the boot 9 in the attachment. This tension device comprises a lever 25 one end of which is hinged at 26 to a lug 27 on the sliding plate 17. This lever 25 is further hinged to one end of a link 28, the other end of which pivots on a sliding block 29 mounted in the slide 18.

The block 29 has a housing with an open end permitting the passage of one end of a spring 30 which is fixed at its other end to the ski 2 through the agency of a screw 31 passing through a hole in the slide 18. The front end of the spring 30 carries a nut 32 in which engages a screw 33 passing through a bore in the block 29. This screw 33 is provided with a knurled head 34 which permits of adjusting the tension of the spring 30 when the attachment is in the operative position.

The lever 25 constitutes, with the link 28, a knuckle-joint. When the lever 25 is lowered from the position shown in FIG. 3 in order to bring it into the position shown in FIG. 1, a movement of the stop element 13 is brought about in the direction of the heel-piece. When the stop element 13 abuts the toe of the boot 9 it becomes stationary and by continuing to lower the lever 25 a movement of the block 29 is produced towards the front of the ski, against the action of the spring 30 which tautens.

It is to be noted that in the case of exaggerated stresses of the boot in the longitudinal median plane of the ski, as well forwards as backwards, the stop element 13 moves forwardly against the action of the spring 30 and permits the boot to be freed.

In the case of a forward fall, the rib 7 of the heel-piece 3 frees itself from the groove 8 of the heel, during a movement of the boot forwards, against the action of the spring 30.

In the case of a backward fall, the toe of the boot, acting on the inclined plane 14 of the stop element 13 moves the latter forwardly, against the action of the spring 30 thus releasing the boot from the attachment.

A strap 35 (FIG. 1) is fixed to the heel-piece and surrounds the boot in order to avoid a total loss of the ski when the boot is released from the attachment.

55 I claim:

1. A safety attachment for skis comprising a base plate, a holding member having an arcuate portion designed to engage an arcuate groove in the heel of a ski boot, said arcuate portion being substantially parallel to said base plate, guide means permitting said holding member to move toward and away from said base plate while maintaining said arcuate portion in a position substantially parallel to said base plate, means for biasing said arcuate portion in the direction of said base plate and means for pushing the front end of the boot rearwardly so as to engage the heel against said holding member, said means for pushing the front end of the boot rearwardly comprising a slide adapted to be fixed to the ski, a member slidably mounted on said slide, a lever hinged at one end thereof to said sliding member, a block slidably mounted in said slide, at least one link

hinged at one end thereof to said lever and at the other end thereof to said block, a spring disposed in said slide for biasing said block in the direction of said holding member, a threaded rod disposed perpendicular to the surface of the ski and secured to said sliding member, a threaded sleeve engageable with said rod, means for maintaining said sleeve in position, a supporting member pivotally mounted on said sleeve and provided with a bore therein, a ball and a spring being housed in said bore, said sleeve having a housing therein disposed opposite said bore so that said ball is biased by said spring into said housing, means for adjusting the tension of said spring, said supporting member being disposed to cooperate with the front of the boot so as to move the same rearwardly, said supporting member having a bearing surface thereon inclined relative to the longitudinal axis of said threaded rod and approaching said axis in the direction of said slide.

2. A safety attachment for skis, as defined in claim 1, further comprising a nut integral with one end of said spring disposed in said slide, a screw engaged in said nut and passing through a bore in said block and the head of said screw bearing against a face of said block.

3. A safety attachment for skis, comprising a heel retaining member, means for securing said retaining member in a preselected longitudinal position on a ski, a slide secured to the ski forwardly of said heel retaining member, support means slidably mounted in said slide, a stop element pivotally mounted on said support means, resilient means for maintaining said stop element in a predetermined angular position on said support means, spring means for releasably engaging said stop element with the toe portion of a ski boot and for simultaneously releasably engaging the heel portion of the ski boot with said heel retaining member, said stop element comprising a convexly arcuate tapering boot bearing surface and an outwardly extending convex lip disposed completely about said boot bearing surface in continuously overhanging relation thereto, whereby the tapering inclination of said boot bearing surface is directed towards said support means.

4. A safety attachment for skis, comprising a heel retaining member, means for securing said heel retaining member in a preselected longitudinal position on a ski, a slide secured to the ski forwardly of said heel retaining member, vertically disposed support means slidably mounted in said slide, a stop element pivotally mounted on said support means, means mounted on said stop element and being disposed in cooperating engagement with said support means for selectively maintaining said stop element in a predetermined angular position on said support means, spring means for releasably engaging said stop element with the toe portion of a ski boot and for simultaneously releasably engaging the heel portion of the ski boot with said heel retaining member, said stop element comprising a convexly arcuate tapering boot bearing surface and an outwardly extending convex lip disposed completely about said boot bearing surface in continuously overhanging relation thereto, whereby the tapering inclination of said boot bearing surface is directed towards said support means.
